Dec. 1190

J. C. Cambridge, Jr. of Enfield, N. H.
Letters Patent No. 1190. Dated Janst 24, 1860,

The schedule referred to in these Letters Patent and making part of the same.

To all whom it may concern:

Be it known that J. C. Cambridge, Jr. of Enfield, in the County of Grafton, and State of New Hampshire, have invented or produced a new and original design for a Bedstead, and I do hereby declare that the following is a full, clear and exact description of the same, reference being had to the annexed drawings making a part of this specification, in which

Figure 1. is an end view of a bedstead showing my design.

Figure 2. a longitudinal vertical section of ditto, taken in the line X. X. figure 1. Figure 3. and 4. Enlarged sections of portions of ditto.

Similar letters of reference indicate corresponding parts in the several figures.

This design for a bedstead comprises the embellishment of the head and foot boards, that is, the exposed sides of the same; to wit: the inner side of the head-board and the outer side of the foot board, together with ornamental sinuous rails which form the boundary of their upper edges.

A. represents the head-board of the bedstead, the inner side of which board has three panels a. a. a. formed in it, said panels being

of rectangular form, of equal dimensions, and quite narrow in proportion to their height, as shown clearly in figure 1.

In each panel a, there is a projecting moulding b, which has parallel sides and semi-circular ends. The faces of these mouldings are of cyma-reversa form as shown clearly in figure 4, and they extend nearly the whole height of the panels a, as shown clearly in figure 2.

The top of the head-board A, has a sinuous rail B, fitted on it. This rail transversely is formed of three semi-circles which when viewed longitudinally form a three beaded rail, the beads being of equal dimensions.

The rail B, projects upward or is the highest at its central part as shown clearly in figure 1.

The foot board C, of the bedstead does not extend as high as the head-board A. The former however is surmounted by a sinuous rail D, which is precisely of the same form as the rail B, but is rather more sinuous, or has greater or quicker curvatures than B, as shown clearly in figure 1. The outer side of the foot board C, has two panels c.c. in it. These panels are of rectangular form of equal dimensions, but their width considerably exceeds their height as shown clearly in figure 1.

The panels c.c. have each a projecting moulding d, within them, which are of an oval or approximate form.

The faces of these mouldings are each of a cyma-reversa form as shown in figure 3.

The head and foot boards are secured or fitted between posts E. The latter however form no part of the design.

What I claim as new and desire to secure by Letters Patent, is— The configuration of the head and foot boards A, C, the same comprising the panels, moulding and sinuous rails, as shown and described to form a new and original design for a bedstead.

Mitnesses.
